WASHING MACHINE FOR TUMBLERS AND
SIMILAR TABLEWARE

Arthur F. Partridge, St. Paul, Minn.

Application November 12, 1934, Serial No. 752,600

4 Claims. (Cl. 15—76)

It is an object of this invention to provide a compact and efficient machine for rapidly and thoroughly cleansing drinking glasses, tumblers and like small receptacles and tableware.

Other objects will appear and be more fully pointed out in the following specification and claims.

Referring to the accompanying drawings which illustrate the best form of my device at present known to me;

Figure 1 is a side elevation of the machine with one of the brushes in central vertical section;

Fig. 2 is a part rear elevation and part vertical section through the casing of the machine;

Fig. 3 is an isometric view of the main clamp member;

Fig. 4 is a side elevation of the machine showing it in the operating position and mounted on a sink or other receptacle for the washing fluid;

Fig. 5 is an isometric view illustrating the main body of one of the rotary brushes;

Fig. 6 is a quarter section through one of the rotary brush tips, and

Fig. 7 is a diagrammatic bottom view illustrating the operation of the rotary and stationary brushes on a pair of the receptacles to be cleansed.

The machine has a pair of spaced, parallel, power-driven shafts 10 and 11 carrying rotary brushes 12 adapted to fit within the interior of a pair of tumblers or like receptacles 13 to be cleansed. Rigidly mounted between and in parallel relation to the shafts 10 and 11 is a third shaft 14 carrying a stationary brush 15 for cleansing the exterior of the receptacles 13. All three brushes extend along their supporting shafts a sufficient distance to reach from the bottom to the top of the receptacles 13.

The shaft 14 is fixed on a removable cover 16 of a housing 17 containing driving connections between a power shaft 18 and the shafts 10 and 11. The shaft 18 projects from an electric motor 19 which is supported on the housing 17. Driving connections for the shafts 10 and 11 comprise a pulley 20 fixed on the shaft 18 and pulleys 21 and 22 secured to shafts 10 and 11 respectively and driven by belts 23 severally trained on the pulleys 20 and 21, and 20 and 22, as shown in Fig. 2.

The casing 17 is formed with a pair of lugs or ears 24 for pivotally connecting the motor and housing to a clamp member indicated generally by the numeral 25. A pivot bolt 26 extends through perforations in the ears 24 and through

a bearing 27 (Fig. 3) formed on the clamp member 25. The edge of a sink, drainboard or other suitable support for the machine may be clamped between a jaw 28 formed on the clamp member 25 and a clamp bolt 29 threaded in the clamp member and having a wing head to facilitate manual operation. A rest 30 is formed on the clamp member to support the motor in idle or inoperative position.

To facilitate moving the motor and brush assembly from inoperative to operative position, I provide parallel arms 31 which extend at opposite sides of the motor and are pivotally connected by a bolt 33 to opposite ends of bosses 32 (Fig. 3) formed on the clamp member 25. The free or rear end of the arms 31 are joined together by a handle 34 and each of the arms 31 is formed with an elongated slot 35 to receive a stud 36 which projects from the side of the motor casing. One of these studs 36 projects from the outer face of the arm 31 to engage the plunger 37 of an electric switch 38. The switch 38 is connected in the current supply circuit for the motor 19 and is so constructed that the motor is started and operated when the switch plunger 37 is released. When the motor is in the idle or inoperative position shown in Fig. 1, the stud 36 is in engagement with the plunger 37 so as to retain the switch 38 in open position and when the motor is tilted to the operative position shown in Fig. 4, the stud 36 releases the plunger 37 to thereby close the switch and operate the motor.

To facilitate the repair or replacement of the rotary brushes 12 when they become worn, I prefer to construct them as indicated in Figs. 1, 5 and 6. Each brush head has a body portion 39 formed with a central bore to receive the shaft 10 or 11 and a transverse slot 40 communicating with the bore to receive a cross pin 41 projecting from the supporting shaft for establishing the driving connection between the shaft and brush body. The head portion 42 of the brush is separable from the body portion 39 and has a threaded bore to receive and engage a threaded end of the shaft 10 or 11. Both the body and head portions of the brush are designed to have groups of bristles secured thereto in longitudinal slots 43 formed in ribs 44 extending longitudinally of the brush body and head. Each of these ribs is arranged to receive a row of bristles set in a strip or insert fastened in the slot 43 by suitable means. The greatest wear takes place on the head of the brush where it engages the bottom of the receptacles and my

construction of the brush is such that the head portion may be quickly and easily removed for replacement or repair independently of the body portion of the brush.

- 5 5. In operation, a pair of the tumblers or other receptacles 13 to be cleansed are inverted upon the rotary brushes 12 with the machine in the idle position indicated in Fig. 1, said brushes extending to the inner surfaces of the bottoms of 10 the receptacles and the brush 15 engaging the exterior surfaces of both receptacles. Now, by grasping the two receptacles 13 and tilting the receptacles are partially or wholly submerged in 15 the cleaning fluid or wash water, the motor is automatically started and the brushes 12 are rotated rapidly. The operator, by grasping the exterior of the receptacles retains them against rotation while the interior surfaces are quickly 20 and thoroughly cleansed and then by partially releasing the gripping pressure, the rotary brushes are allowed to rotate the receptacles in the hands of the operator so that the exterior surfaces are rotated and cleansed by contact with 25 the stationary brush 15. After a few revolutions of the receptacles in the washing solution the machine is returned to its inoperative position where the switch 38 opens the circuit and the receptacles 13 are then removed from the brushes. 30 It will be understood that the entire cleaning operation is performed quickly and easily, without danger of breaking the receptacles. Thus the machine is adapted for use in cleaning delicate glass and chinaware.
- 35 35. Having described my invention, what I claim as new and desire to protect by Letters Patent is:
  1. A machine of the class described having in combination, a support, a motor movably attached to said support, means for securing said support on a container for cleaning fluid, a shaft operatively connected to said motor, a cleaning member mounted on said shaft and formed to fit within receptacles to be cleansed, said cleaning member being arranged to be submerged in cleaning fluid 40 in said container and raised above the surface thereof by appropriate movement of said motor a switch in circuit with said motor for controlling the same and a member movable with said motor and positioned to engage said switch to start and stop said motor respectively upon movement of said cleaning member to and from submerged position.

2. In a machine for washing tumblers and like receptacles, a clamp adapted to be secured to a container for cleaning fluid, a motor pivotally mounted on said clamp, a pair of parallel shafts operatively connected to said motor, cleaning heads mounted on said shafts and formed to fit within a pair of receptacles to be cleaned simultaneously, a stationary cleaning element positioned between said cleaning heads to engage the exterior of said receptacles simultaneously and means for pivoting said motor to submerge said receptacles and cleaning heads in cleaning fluid in said container.

3. In a machine for washing tumblers and like receptacles, a support adapted to be secured to a container for cleaning fluid, a motor pivotally mounted on said support, a pair of parallel shafts operatively connected to said motor, cleaning heads mounted on said shafts and formed to fit within a pair of receptacles to be cleaned simultaneously, a stationary cleaning element positioned between said cleaning heads to engage exterior surfaces of said receptacles simultaneously, said motor being pivotal on said support to submerge said receptacles and cleaning heads and element in cleaning fluid in said container, an electric switch in circuit with said motor for controlling the operation thereof and a member movable with said motor and positioned to engage said switch to start said motor when said heads are moved to submerged position.

4. In a machine for washing tumblers and like receptacles, a support adapted to be secured to a container for cleaning fluid, a pair of substantially parallel shafts, means movably securing said shafts to said support and permitting said shafts to extend obliquely downward into said receptacle for cleaning fluid, cleaning heads mounted on said shafts to be submerged in said cleaning fluid in said container and formed to fit within a pair of receptacles to be cleaned simultaneously, cleaning means arranged to engage the exterior of said receptacles in said cleaning fluid, an electric motor, means operatively connecting said shafts to said motor and a switch in circuit with said motor, a member movable with said motor and positioned to engage said switch upon movement of said heads to and from submerged position to start and stop said motor respectively.

ARTHUR F. PARTRIDGE.
